UNITED STATES PATENT OFFICE.

TOM FREDERICK GRAY, OF MANCHESTER, ENGLAND, ASSIGNOR TO ELIZABETH ANNE BOLTON, OF MANCHESTER, ENGLAND.

STEAM-SUPERHEATER.

1,129,667.

Specification of Letters Patent.

Patented Feb. 23, 1915.

Application filed August 31, 1914. Serial No. 859,476.

To all whom it may concern:

Be it known that I, TOM FREDERICK GRAY, a subject of the King of Great Britain and Ireland, and resident of 49 Deansgate, in the city of Manchester, England, have invented certain new and useful Improvements in Steam-Superheaters, of which the following is a specification.

This invention relates to superheaters for marine, locomotive, water tube and land types of generator, and has for its object to provide an improved arrangement of Field tube superheater which shall be efficient in action.

15 My invention comprises the improved arrangement hereinafter described and claimed for connecting Field tube superheating elements in series between headers.

Referring to the accompanying sheets of explanatory drawings:—Figure 1 is an end elevation of a marine type boiler having a superheater, constructed in accordance with my invention, applied thereto. Fig. 2 is a sectional plan view of a portion of the marine boiler shown at Fig. 1 with part of the superheater in section. Fig. 3 is a detail view of a superheater element and Fig. 4 a detail view of the means for maintaining the concentricity of the tubes. Fig. 5 is an elevation, with a part cut away, of a marine type boiler having a modified form of my improved superheater applied thereto. A portion of the superheater tubes is cut away for the sake of clearness. Fig. 6 is a sectional plan view on the line A—B of Fig. 5 of a portion of the boiler and superheater. Fig. 7 is an end elevation, Fig. 8 a plan view and Fig. 9 a sectional side elevation of my improved superheater applied to a land type boiler.

The same reference letters in the different views indicate the same or similar parts.

In the application of my invention to a Scotch or marine type boiler, as shown at Figs. 1 to 4, I provide adjacent to the front end of the boiler *a*, which may for example have three furnaces *b*, and three sets of return fire tubes *c*, headers *d* and *e*, the latter being disposed in pairs with two pairs in each division between the tube stacks. One header of each pair as for example *d*, forms a saturated steam inlet header while the other header of each pair as for example *e*, forms a superheated steam outlet header. Each inlet header communi-

cates by means of a plurality of tubes as *f* with a plurality of sets of Field tubes, each Field tube extending into a fire tube of the boiler. The connection with the inlet header *d*, may for example lead to the inner or 60 smaller diameter tube *g* of a Field tube, the larger diameter tube communicating by a branch connection *h* with the large diameter tube *i* of the adjacent Field tube. From the smaller diameter tube *g* of the latter the 65 steam may be conveyed to another pair of Field tubes or to any desired number of Field tubes arranged in a similar manner. A set of four Field tubes is shown in Fig. 3. The steam is then passed into the outlet or 70 superheated steam header *e*.

The arrangement of the groups of Field tubes varies with the disposition and number of the boiler fire tubes. Preferably the Field tubes are disposed at each side of the 75 headers, the central stack of fire tubes receiving Field tubes in connection with both headers. The concentricity of the fire tubes and outer and inner tubes of each Field tube is maintained by means of nodes 80 *j* as shown in Figs. 4.

Instead of having simple inlet and outlet headers as aforesaid, I may, as shown in Figs. 5 and 6, provide headers *d*, each having three compartments or divisions, one 85 division *k* serving to pass the saturated steam through one set or series of Field tubes to an intermediate compartment *m* from which the steam passes through a further set or series of Field tubes to the outlet compartment *n* 90 of the header. In this way, I obtain a double circulation through the header. I may, however, provide for a triple or other circulation if desired.

My improved arrangement can be applied 95 to Scotch boilers having any usual number of furnaces and fire tube stacks, and also to locomotive or other types of boiler.

The application of my improved superheater to a land type boiler is shown in 100 Figs. 7, 8 and 9. The superheater elements which are similar to the one shown in Fig. 3, but provide for the subjection of the steam twice to the action of the hot gases, are attached to the headers *d*, *e* and held in 105 place by bridge pieces *p*.

By the arrangement of the Field tube superheater elements as aforesaid, I provide for the subjection of the steam on a plurality of occasions to the hot gases without 110

the necessity for employing intermediate distributing headers. In the arrangement shown at Figs. 5 and 6, the distributing headers provide for a very large number of 5 circulations of the steam through Field tubes but such will not usually be requisite.

Having now described my invention, what I claim as new and desire to secure by Letters Patent is:—

19. 1. A steam superheater comprising, in combination, saturated and superheated steam passages and at least two Field tube elements connected to said passages only by their inner small diameter open ended tubes, and interconnected independently of said passages by their outer tubes, as set forth.
2. A steam superheater comprising in combination, saturated steam inlet and superheated steam outlet passages, at least 20 two Field tube elements connected to said passages only by their inner small diameter

open ended tubes, and tubular conduits interconnecting the outer large diameter tubes of the Field tubes, as set forth.

3. A steam superheater comprising in 25 combination, a header with saturated steam inlet and superheated steam outlet compartments, at least two Field tube elements through which steam circulates in series between said compartments, said elements being connected to the header only by their inner small diameter tubes but being interconnected by their large diameter tubes, as set forth.

In testimony whereof I have signed my 35 name to this specification in the presence of two subscribing witnesses.

TOM FREDERICK GRAY.
